BENJAMIN F. SCHMIDT, OF SOUTH PASADENA, CALIFORNIA.

GEAR-SHIFT MECHANISM.

Application filed November 3, 1920. Serial No. 421,581.

This invention relates to improvements in gear shifts and refers more particularly to a mechanism for effecting the different speed changes in vehicles using a selective type transmission for producing speed changes.

Among its salient objects are to provide a shift mechanism which effects the gear change in a selective speed transmission with the pushing down of the clutch pedal and disengagement of the clutch; to provide a gear change mechanism that is positive in its operation and one that permits of the meshing of the gears in shifting by "feeling" the gears into engagement by proper pressure of the driver's foot on the clutch pedal; to provide a gear shift mechanism that is operated automatically with the actuation of the clutch pedal, the desired speed change having been previously selected by a small lever mounted on the steering post, or operated by using the common type of gear shift lever inserted into an engagement slot and the shift made by hand in the usual manner; to provide a mechanism that registers automatically the speed in which the transmission is geared or whether it is in a neutral position, a mechanism that provides a neutral position for each speed effected by a partial throw of the clutch pedal; to provide a mechanism that is cheap to manufacture in that the parts may be made stamped from the metal into the desired shapes and forms; to provide a shift that advances progressively through the respective gear changes, but may be operated selectively in coming down the speeds from high to reverse.

In the drawings:

Fig. 1 is a side elevational view showing the interior mechanism of the shift.

Fig. 2 is a rear end view with the casing of the gear mechanism cut away to expose the interior parts.

Fig. 3 is a view similar to that in Fig. 2 with interior parts, shown in Fig. 2, omitted to disclose the shifter arm mechanism.

Fig. 4 is a detail of the squared shaft and sleeve members for the hand lever attachment.

Figs. 5 and 6 are fragmentary details of the pivoted shifter arms.

Fig. 7 is a plan view showing the interior mechanism of the shifter.

Figs. 8 and 9 are details of the selector device.

Fig. 10 is a view showing the interlocking mechanism.

Fig. 11 is a plan view of a portion of the chassis of an automobile showing the position of mounting the shift and appurtenant parts.

Fig. 12 is a fragmentary detail of the engagement of the lower extremities of the shifter arms with the flanged lugs of the shifter forks.

Figs. 13 and 14 are details of a spring device shown at the lower end of the selector rod manipulated by the lever handle on the steering post.

Fig. 15 is a detail of the lever handle mounted on the steering post.

Fig. 16 shows the connection of a shift mechanism with a clutch pedal.

Figs. 17 and 18 are details of the registering device mounted on the dash for informing the driver the speed in which the car is running.

Referring to the drawings, the shift may be mounted in any convenient position on the transmission casing of a vehicle using the selective type transmission.

The shift mechanism or casing 1 must be so mounted upon the transmission casing that the shifter forks 2 and 3 engage the two sliding gears in the transmission casing (not shown) which when moved to different positions produce the various speeds. The shifter fork 2 controls the gear producing reverse and low speeds while the shifter fork 3 regulates both intermediate and high. These shifter forks are constructed with flanged lugs 4 and 5 which slide in the slots 6 and 7 in the lower plate 8 of the shifter mechanism.

The upper flanges 9 and 10 of the respective shifter fork lugs are notched at 11 to accommodate the wedge shaped portion of the pivoted locking members 12. These locking members 12 are pivoted on either side of the flanges at 13 and are kept in contact with them by springs 14. (See Fig. 10.) Thus, when a gear has

been selected and the shift made, this locking member will hold the shifter fork in place until another shift is affected. An interlock 15 transversely slid able in a block 16 and engaging cut out portions 17 and

18 in the respective flanges, serve to hold the shifter fork which is not being shifted in a rigid position while the other is being moved.

5 The shifter mechanism itself comprises a plurality of pivoted arms 19, a shifter frame 20, a selector 21, a selector guide 22, slidably mounted on a guide support 23, a series of guides 24 for pivoted arms 19, a neutralizer 10 25 and a slidable latch member 26 mounted upon the neutralizer.

The pivoted arms 19, 19^a, 19^b and 19^c are extensions of two sets of interconnected members 27, 28, 29 and 30. The lower extensions 31 and 32 of the members 27 and 29 are shaped to fit into slots 33, and 34, in the respective shifter fork lugs 4 and 5 and by their movement operate the shifter forks to produce the gear change in the 20 transmission casing. The member 27 comprises the lower extension 31 which fits into the lug of the shifter fork, and a turn back portion 35 which together with the main portion of the member is secured upon 25 the shaft 36 by means of woodruff key 37. In the extremity of the turn-back portion 35 is a pin 38 which pivots the same to the bent-back portion 39 of the member 28 the latter engaging the pin by means of a slot 30 40 cut in its extremity. In the member 27 is also cut a slot 41 which is in the form of an arc of a circle accommodating the shaft 42 which extends therethrough and permits the movement of the member 27 on 35 its pivot 36. The member 28 which is pivoted to freely rock upon the shaft 42 has an arm 19^a identical to the upstanding arm 19 of the member 27. These arms each have an upward and downward movement be- 40 tween the guide members 24. It is obvious that by moving either of the arms 19 or 19^a said movement will be transmitted to the extension 31 of the member 27 through the pin connection 38 of the two interconnected 45 portions of the two members. It will further be evident that as the arm 27 with its turn-back portion 35 rocks with the shaft 36, and as the arm 28 with its bent-back portion 39 is freely pivoted on the lower shaft 42, the 50 intermediate pin and slot connection 38 and 40 will cause the arms 19 and 19^a to move simultaneously in opposite directions; that is, whenever one of the arms 19, 19^a moves upwardly, the other thereof will move down- 55 wardly from an intermediate or neutral position. In a like fashion the member 29 has a bent-over portion 43 which is pivoted to a square sleeve 44 and is pivotally connected to a similarly bent-over portion 45 of the 60 arm 30 by a pin 46. The member 29 has an upstanding arm 19^b and the member 30 a similar arm 19^c, both of which are movable between guide members 24 identical to those guiding the upstanding arms 19 and 19^a. 65 The member 29 has a slot cut in the form

of an arc similar to that shown at 41 in the member 27 to accommodate the shaft 42. The member 30 is pivoted to freely rock upon the shaft 42 in the same manner as the member 28. Also the movements of the up-standing shifter arms 19^b and 19^c are transmitted (in the same manner as above explained in connection with the arms 19 and 19^a) through the pin connection 46 of the interconnected portions of the members 70 30 and 29 to the lower extremity 32 of the member 29 which fits in the slot 34 of the flanged member 9. The shifter fork controlling the intermediate and high gears being a part of this flange, is moved to positions of engagement or disengagement with the low or high gears according to its movement.

In Figs. 1, 2 and 4, the several arms 19 to 19^c are shown in their neutral positions 85 and particularly in Figs. 1 and 10, the gear shifting forks are also shown in neutral positions. Assuming that the arm 27 shifts the fork 2 rearwardly (to the left in Fig. 1) for reverse and forwardly for low, and that the arm 29 shifts the fork 3 rearwardly for intermediate and forwardly for high, it will be evident, with reference to Fig. 2, that an elevation of the arm 19 by the selector 21 will throw the fork actuating arm 27 rearwardly and shift the fork 2 to reverse position. At the same time the arm 19^a will be lowered due to its intermediate pin and slot connection with the arm 27. Similarly, when the arm 19^a is elevated the arm 19 will be lowered and will throw the fork actuating arm 27 forwardly and shift the fork 2 to low position. The respective movements of the arms 19^b and 19^c are identical to those of the arms 19 and 19^a to throw the fork actuating arm 29 rearwardly or forwardly to shift the fork 3 to intermediate or high positions.

It will be noted at this time that the member 27 is pivoted on the shaft 36 while the member 29 is pivoted on the square sleeve 44 rotatably mounted upon the shaft 36. The shafts 36 and 42 are both rotatably mounted in the gear shift casing 1. A lug 47 is fixedly attached to the sleeve 44 110 and a similar lug 48 is fixed to the shaft 36. These lugs have cut-out portions 49 which permit the vertically pivoted hand lever 50 to be moved from engagement with one of the cut-out portions to the other. When the lever is in a position shown in Fig. 3, in engagement with the lug 47, the actuation of the hand lever will rotate the sleeve 44 transmitting this motion to the shifter fork 3 thereby controlling the transmission mechanism in intermediate and high gear. When the lever is moved into engagement with the lug 48, its operation will actuate the shifter fork 2 and operate to shift the transmission in reverse and low gears. A 120

button 51 is held in contact with the vertical hand lever by means of spring 52. The neutral position of the lever will be that at which the two cut-out portions of the lugs 57 and 48 register at which time the lever may be moved into engagement with either lug. This hand lever is merely an emergency attachment and may be used or not as desired. However, it is important that this mechanical shift may be operated automatically from the clutch pedal or by the simple insertion of this vertical hand lever be converted to a simple hand shift in common use at this time.

Prior to making the gear change by means of the clutch pedal, it is necessary that the proper gear be chosen and in order to do this there is mounted upon the steering post 53 a quadrant 54 which has apertures 55 cut in the periphery thereof corresponding with the different gear changes in the transmission. A selector handle 56 is secured at 57 to a rod 57^a journaled in the quadrant and has an upstanding lug 58 in which is fitted a button 59 held in contact with the quadrant by means of spring 60 and forcing the button into the respective apertures corresponding with the different gear changes with the rotation of the handle upon its pivot. The function of this button is to hold the selector handle in a position when a gear has been selected. The rod 57^a upon which the handle is mounted extends along the steering post and substantially parallel thereto and is pivotally mounted in a bearing member 61. To the lower portion of this rod 57^a is attached a disc like casing 62 which contains a coil spring 63. Both ends of this coil spring abut on the two sets of stop pins 64 and 65. Within this casing and adjustably fixed to the rod 57^a by means of a set screw is a lever arm 66 upon which is fixed a narrow lug 67. On the rotation of the rod 57^a the lug upon the lever arm 66 will pass between either of the stop pins according to the direction of rotation and abut against the end of the coil spring thereby imposing a spring tension upon the lever arm. To the lever arm 66 is attached a stiff wire 67^a passing through a hollow tube 68 to the shift mechanism. This wire is attached to the selector guide 22 by means of connecting plate 69. This selector guide is slidably mounted upon the guide rod 23 and may be moved from side to side across the gear shift mechanism in the selection of the gears. The extremity of the guide 22 rides in a slot 70 running transversely of the gear shift mechanism. The function of this slotted guide is to stiffen the construction and hold the guide in position. The guide 22 is longitudinally slotted to permit the raised lug 71 of the selector 21 to slide back and forth therein with the movement of the frame 20. By sliding the guide to

any position desired by means of the hand lever through the connections explained, the selector is moved due to the sliding engagement of the lug 71 and slot of the guide, to a position substantially in vertical alignment with any one of the shifter arms 19, 19^a, 19^b or 19^c so that when the frame 20 is actuated, the arm chosen according to the selective positioning of the selector will be contacted by said selector.

The selector 21 comprises a triangular shaped projection 72 and an upper lug 71 its intermediate portion being a narrow flanged construction 73 slidably mounted in a slot 74 in the shifter frame 20. The shifter frame is a U-shaped member having both ends fixedly attached to and pivoted upon the shaft 42. The frame 20 abuts upon a support 75 which has a T-shape, the cross member of said T providing the abutment for the frame and the longitudinally extending leg 76 supporting the guides 24 and slotted to permit the projection of the arms 19, 19^a, 19^b and 19^c therethrough.

Inside of this shifter frame 20 is a smaller U-frame or neutralizer 25 which has its two ends rotatably mounted upon the shaft 42. This neutralizer abuts upon an angle plate 77 in one position and against the front of the shifter arms when the frame 20 is actuated to affect the gear change.

Extending transversely of the gear shift mechanism and through two slotted apertures 78 in both legs of the neutralizer is a latch 26 having an elongated head 26^a. This latch is held in position in the neutralizer by a flat spring 26^b which is riveted to one of the lower legs of the neutralizer and fits into a slot in the body of the latch. This spring keeps the elongated head 26^a in contact with the adjoining lug of the neutralizer shown in Fig.

7. An S-plate 79 fixed to a leg of the larger shifter frame contacts the elongated head of the latch member thus carrying the neutralizer with the shifter frame when it is actuated by the clutch pedal.

Describing now the actuation of the shifter frame upon its pivot 42 subsequent to the selection of the desired gear by means of the selector 21, attention will be directed to the fact that the frame is fixedly attached to the shaft 42 which extends outside of the gear shifting casing. On the end of this shaft extension is a pinion 80. This pinion is so mounted that when the clutch pedal 81 pivoted at 82 is pushed down disengaging the clutch, the teeth 83 which are internally milled on the sector 84, the latter being part of the clutch pedal and pivoted at 82, mesh, the internal gear 80 is rotated causing the shaft 42 to rotate in the direction shown by the arrows. A portion of this internal surface of the sector 84 as shown at 85 is not milled with gear teeth thereby permitting the clutch pedal to be partially pushed down and the clutch released before the gear

is engaged.

Describing now the actuation of the shifter frame upon its pivot 42 subsequent to the selection of the desired gear by means of the selector 21, attention will be directed to the fact that the frame is fixedly attached to the shaft 42 which extends outside of the gear shifting casing. On the end of this shaft extension is a pinion 80. This pinion is so mounted that when the clutch pedal 81 pivoted at 82 is pushed down disengaging the clutch, the teeth 83 which are internally milled on the sector 84, the latter being part of the clutch pedal and pivoted at 82, mesh, the internal gear 80 is rotated causing the shaft 42 to rotate in the direction shown by the arrows. A portion of this internal surface of the sector 84 as shown at 85 is not milled with gear teeth thereby permitting the clutch pedal to be partially pushed down and the clutch released before the gear

is engaged.

Describing now the actuation of the shifter frame upon its pivot 42 subsequent to the selection of the desired gear by means of the selector 21, attention will be directed to the fact that the frame is fixedly attached to the shaft 42 which extends outside of the gear shifting casing. On the end of this shaft extension is a pinion 80. This pinion is so mounted that when the clutch pedal 81 pivoted at 82 is pushed down disengaging the clutch, the teeth 83 which are internally milled on the sector 84, the latter being part of the clutch pedal and pivoted at 82, mesh, the internal gear 80 is rotated causing the shaft 42 to rotate in the direction shown by the arrows. A portion of this internal surface of the sector 84 as shown at 85 is not milled with gear teeth thereby permitting the clutch pedal to be partially pushed down and the clutch released before the gear

is engaged.

change is affected, this latter taking place when the pinion 80 is rotated by meshing with the internal gear teeth 83. The rotation of this shaft actuates the frame member 20 which by means of the selector contacting one of the shifter arms produces a gear change. The neutralizer 25 which is carried by the frame 20 operates to bring all of the shifter arms to a neutral position prior to the actuation 10 of any shifter arm by the selector member in making a subsequent gear change. More specifically, as the shifter frame 20 is rotated upon its pivot by the disengagement of the clutch, the S-plate 79 contacting the head of the latch 26 moves the neutralizer with it. The neutralizer contacting any of the shifter arms which are out of position due to a previous gear selection brings them all to a neutral position, as shown in 15 Figs. 2 and 3. At this time the elongated head 26^a is contacted by the wedge 86 and moved outwardly against the tension of the spring 26^b until the head has moved far enough so that the S-plate 79 may pass by it thus releasing the neutralizer from the shifter frame. The shifter frame with continued rotation on its pivot 42 contacts, by means of the selector, the selected shifter arm and elevates the same to its extreme 20 position at which time the desired gear change is affected. In returning, the shifter frame must again be positioned relative to the neutralizer so that with a subsequent shift the neutralizer will be in a position 25 to bring the shifter arms again to neutral. That is, the head of the latch must be again in a position in front of the S-plate so that with the actuation of the shifter frame the neutralizer will be carried with it. Therefore as the shifter frame returns to its initial position or that which it assumes when the clutch pedal has been released and the clutch engaged, the opposite end of the latch from that on which the head is mounted 30 contacts a beveled portion 86 on the adjoining leg of the shifter frame 20. This slides the latch member transversely so that the S-plate 79 will pass the elongated head and again assume a position behind the neutralizer. With the passing of the frame 20 the latch due to the spring will again assume a normal position as shown in Fig. 7. Thus 35 in its movement up and down the frame will carry the neutralizer to a position where the latter brings the shifter arms to a neutral position, then releases the neutralizer and affects the shift and on its return operates the latch so that the shifter frame will again be positioned in its initial position 40 relative to the neutralizer.

Between the two lugs of the shifter frame extending transversely of the shift casing is a bar 87 having two stop projections 88 and 89. The function of these stop projections 45 is to produce a progressive selection of gears

when shifting from low to high. More specifically assume that the vehicle is standing and the transmission mechanism is in a neutral position. On entering the car, the driver may immediately select high gear 70 with the selector lever on the steering post. This compresses the circular coil spring and puts a tension upon the lever arm 66 which tension has a constant tendency to pull the selector guide and selector toward high gear. 75 This spring tension causes the selector to be moved against the stop projection 88. The driver has now to push out the clutch pedal which actuates the shifter frame moving the selector forward into the slot occupied by 80 the shifter arm 19^a. The operation of this arm through connections previously explained meshes the gears producing low speed in the transmission. As the clutch pedal is released and the shifter frame returned to its initial position against the abutting stop 75 the selector returning therewith will slide out of the slot in which the low speed shifter arm is positioned and due to the spring tension on the coil spring will 85 drop against the next stop projection 89. Then without further moving of the selector lever on the steering post, the clutch pedal may be again pushed down at which time the clutch is disengaged and the shifter frame will carry the selector into the next 90 adjoining slot in which the intermediate shifter arm 19^b operates. By again engaging the clutch the selector will ride over the stop projection 89 due to the spring tension 95 previously mentioned and move into a position to be advanced into the slot in which the high speed shifter arm 19^c rides; thus, the successive shifts from reverse or neutral to high gear may be made progressively by 100 simply advancing the selector lever arm on the steering post to the high speed position and then manipulating the clutch pedal as explained as the car gathers its speed. In coming down from high to a lower gear or 105 even to reverse, the selector will drop over the stop projections and preselection of any gear may be accomplished in a selective manner contrasted with the progressive manner of advancing by simply selecting the 110 gear on the steering post and effecting it by means of the clutch pedal.

For the purpose of registering the gear change which has been selected or that which is in mesh, I fasten to each of the 115 flanged lugs 9 and 10 stiff wires 90 and 91. These wires pass through a tube 92 and terminate in a box-like casing 93 mounted upon the dash of the vehicle not shown. In the front of this box is fitted a glass plate 94 120 which exposes an oblong portion of the interior. In the back of the box is fixed an oblong plate of substantially the same size as the front window 94 upon which is written "neutral." At the top of the wire 90 is 125

mounted a sign-plate 95 which is shifted to a position before the window 94 when the gears are shifted in low. A similar sign-plate 96 is mounted somewhat lower upon the wire 90 and when the gears are meshed to produce reverse speed this sign-plate is in a position before the window 94 and easily visible from the driver's seat. In the same manner the sign-plates 97 denoting high 10 and 98 denoting intermediate are mounted upon the wire 91 and adapted to be exposed when the corresponding gears are meshed to produce that speed. When either sign-plate is in position before the window 94 it will 15 cover the neutral plate which is fixedly mounted in the back of the casing. With this simple device the driver is at all times informed of the gear speed which he has in mesh and can make his shifts accordingly. 20 This device, as explained, may be mounted in any position upon the transmission casing so that the shifter forks will engage the slide- 25 gears whose movement makes the different gear changes in the transmission. In the drawings, the mechanism is shown mounted on top of the gear shift casing.

By means of this shift mechanism the driver is relieved of all inconvenience due to the manipulation of the hand lever in shifting gears and has his hands free at all times for steering the vehicle. The shift is positive in that it is effected as the clutch pedal is pushed down and by the gear arrangement meshed directly with the toothed sector fixedly attached to the treadle of the clutch the driver may feel the gears into engagement. It will be noted in this connection that the shift does not rely upon the clutch spring or any associated spring for making the gear 40 change and also that the change is made as the clutch pedal is pushed down and not as it returns to position when the clutch is reengaged. In addition to this the ratchet arrangement which permits a preselection of 45 high gear from reverse and low and a subsequent shift by successive actuations of the clutch pedal is a decided improvement. This ratchet permits of progressively shifting when advancing from low to high gear and 50 a selective change in coming down from high to low. An advantage too in the construction of the device is that most of the parts may be made from stampings and no machine work is required thus making the device 55 very cheap to build.

In the details of construction of this mechanism, I do not wish to limit myself to the specific construction shown except as set forth in the appended claims.

I claim as my invention:

1. In a gear shift mechanism, the combination of: gear shifting forks; interconnected shifter arms for actuating each fork; a shifter frame; a selector member translatable on said frame to positions before any

of said shifter arms and adapted to operate the same with the operation of the shifter frame; a shifter frame operating means; means for imposing translating tension upon the selector member; and means positioned 70 relative to the selector member to insure a progressive shifting from reverse to high driving speeds with successive operations of the shifter frame.

2. In a gear shift mechanism, the combination of: gear shifting forks; pivotally mounted interconnected shifter arms for actuating each fork; a shifter frame operated by the clutch pedal; a selector member translatable on said frame to positions before any 80 of said shifter arms and adapted to operate the same with the operation of the shifter frame; means operable from the driver's seat for imposing spring tension upon the selector member in pre-selecting a desired gear 85 change; and stop means positioned relative to the selector member for determining and directing an advancing progressive shifting of the gears by successive actuations of the clutch pedal until the desired change has 90 been effected.

3. In a gear shift mechanism, the combination of: gear shifting forks; pivoted interconnected shifter arms for actuating each fork; a shifter frame operated by the 95 clutch pedal; a selector member translatable on said frame to positions corresponding to the speed change selected and adapted to operate the selected shifter arm with the operation of the shifter frame; means operable from the driver's seat for imposing spring tension upon the selector member in pre-selecting a desired gear change; and means positioned relative to the selector member for determining and directing the 100 gear shifting progressively in advancing from reverse to high driving speeds and selectively in retarding from high to reverse speeds.

4. In a gear shift mechanism, the combination of: gear shifting forks; pivoted interconnected shifter arms for actuating each fork; a shifter frame operated by the clutch pedal; a selector member translatable on 115 said frame and adapted to be selectively positioned relative to the shifter arm corresponding to the desired speed change and to actuate the same with the operation of the shifter frame; a neutralizer detachably engaged to and operated with the shifter frame through a part of its actuation to neutralize the shifter arms prior to the consummation of a selected gear change; and means for effecting progressive gear changes with a single pre-selection and successive actuations 120 of the clutch pedal.

5. In a gear shift mechanism, the combination of: a gear shifting means; interconnected shifter arms connected therewith; a shifter frame operably connected with the 125

- clutch pedal; a selector member translatable on the shifter frame and adapted to be positioned relative to the respective shifter arms; means cooperating with said selector member to actuate the selected arm with the actuation of the frame; means for imposing a progressive tension upon the selector member; and means positioned relative to said selector member for effecting progressive gear speed changes with the successive operations of the clutch pedal.
6. In a gear shift mechanism, the combination of: gear shifting means; shifter arms for actuating said gear shifting means; a shifter frame connected with the clutch pedal and actuated thereby; a selector mounted on said shifter frame; means for positioning said selector member to actuate predetermined shifter arms; and means for effecting progressive gear speed changes by a single setting of the selector positioning means and successive actuations of the clutch pedal.
7. In a gear shift mechanism, the combination of: a pair of shifter forks; means for actuating said forks, said means comprising pivotally mounted shifter arms connected with said forks, a shaft, a shifter frame on said shaft, a selector slidable on said frame and a gear secured to said shaft; a clutch pedal adapted for an initial movement independent of said gear, for disengaging the clutch; and a toothed member normally out of mesh with said gear and movable with said pedal, said toothed member being arranged to operate idly during such clutch disengaging operation and to subsequently engage and operate said gear during a continued depression of the clutch pedal to effect a gear change.

BENJAMIN F. SCHMIDT.
